SIGNAL TRANSLATING APPARATUS AND
SUPPORTING MEANS THEREFORChester M. Sinnott, Westmont, N. J., assignor to
Radio Corporation of America, a corporation of
DelawareOriginal application October 9, 1941, Serial No.
414,305, now Patent No. 2,376,456, dated May
22, 1945. Divided and this application May 30,
1944, Serial No. 538,073

12 Claims. (Cl. 274—24)

1

This invention relates to signal translating apparatus, and more particularly to a mounting for a signal translating device for use especially in connection with phonograph records, the present application being a division of my copending application Serial No. 414,305, filed October 9, 1941, now Patent No. 2,376,456, granted May 22, 1945.

In my aforesaid copending application, I have disclosed a capacity type pickup, the capacity of which is varied in accordance with the record groove modulation of a phonograph record to provide frequency modulation in an oscillator circuit wherein the pickup constitutes a tuning element. The pickup is carried on the end of a pickup arm which is arranged for swinging movement over a record in customary manner.

The pickup arm arranged as above set forth usually exhibits low frequency resonance. If the pickup is rigidly mounted on the arm, then the pickup arm resonance introduces distortion in the reproduced signal, particularly where, as in the case of the pickup disclosed in my aforementioned copending application, the operating parts have a low mechanical impedance and the needle pressure of which is very low on the record.

The primary object of my present invention is to provide an improved pickup mounting on the pickup arm by means of which distortion due to low frequency pickup arm resonance will be reduced to a minimum.

More particularly, it is an object of my present invention to provide an improved pickup mounting which will serve effectively to isolate vibrations of the pickup arm, particularly at the low resonant frequency thereof, from the pickup.

Another object of my present invention is to provide an improved pickup mounting as aforesaid which is relatively stiff torsionally, so that resonant torsional vibration will not be imparted to the pickup.

Still another object of my present invention is to provide a pickup mounting as above set forth which is very simple in construction, inexpensive in cost, and highly efficient in use.

In accordance with my present invention, the pickup unit is mounted in a suitable head or frame to each side of which is secured a flat spring of phosphor bronze or the like. The springs extend from the frame in parallel relation and straddle the free end of the pickup arm, being secured to the pickup arm at their opposite ends. The springs are so disposed that they extend in parallel planes normal to a plane transversely through the pickup arm, and they

5 maintain the pickup head or frame in spaced relation to the pickup arm. Flat springs are employed so that the unit will be stiff torsionally. However, the pickup unit is yieldably mounted in a direction transverse to the pickup arm, and therefore vibration of the arm due to swinging movement thereof over the record will be very greatly attenuated and will not materially affect the pickup. The connecting springs are preferably damped by securing thereto, at appropriate points, a damping material having suitable damping characteristics. With an arrangement of this sort, the system may be made to cut off at a frequency considerably above the 10 low frequency resonant frequency of the pickup arm.

15 The novel features that I consider characteristic of my invention are set forth with particularity in the appended claims. The invention, itself, however, both as to its organization and method of operation, as well as additional objects and advantages thereof, will best be understood from the following description of one embodiment thereof, when read in connection 20 with the accompanying drawing, in which

25 Figure 1 is a side elevation of a pickup mounted on a pickup arm in accordance with one form of my present invention.

30 Figure 2 is an enlarged, top plan of the forward end of the pickup arm, the pickup unit, and the mounting therebetween,

35 Figure 3 is a side elevation, partly in section, of the structure shown in Fig. 2, and

40 Figure 4 is a set of curves showing the resonance of the pickup under various conditions both with and without a mounting according to the present invention.

45 Referring more particularly to the drawing, wherein similar reference characters designate corresponding parts throughout, there is shown a pickup arm 1 pivotally mounted on a horizontal pivot 3 which is formed on the upper end of a yoke 5 having a downwardly extending, vertical pin or post 7 received in the vertical bearing 9 of a standard 11. By reason of the pin or post 7 in the bearing 9, the arm 1 is free to swing in a horizontal plane over a phonograph record (not shown). At the same time, the arm 1 is free to swing in a vertical plane on the horizontal pivot 3.

50 A pickup device 13, preferably but not necessarily of the capacity type such as that disclosed and claimed more particularly in my above identified copending application, is clamped in a head or frame 15 by a plurality of screws 17. The

pickup 13 includes a needle 19 adapted to cooperate with and to be vibrated by the modulated groove of a phonograph record to thereby set up signal voltages. The head or frame 15 is secured to the arm 1 by means of a pair of leaf springs 21 of phosphor bronze or the like. The springs 21 are secured adjacent one end to the head 15 and extend therefrom in parallel relation. As will be seen from Fig. 2, the springs 21 straddle the forward or free end of the pickup arm 1 and their opposite ends are secured to a pair of blocks 23 carried by the pickup arm 1.

The springs 21 are disposed in planes parallel to a plane which extends transversely through the pickup arm 1 and they maintain the head 15 in spaced relation to the adjacent end of the arm 1. Thus, it will be apparent that the head 15 and the pickup 13 are yieldably mounted for movement in a direction transversely of the arm 1, that is, in a plane parallel to the plane of the record. At the same time, since the leaf springs 21 are disposed in planes normal to this transverse direction, they are relatively stiff torsionally. Preferably, although not necessarily, a pair of strips or blocks of damping material 25 are secured at their ends to the springs 21 by a suitable adhesive 27. The damping members 25 extend between the pickup frame or head 15 and the blocks 23 and are shown mounted on the inside surface of each of the blades 21. However, it is apparent that the damping blocks 25 may be mounted on the outside surfaces of the springs 21 and may or may not engage the spring blades 21 along the entire lengths thereof, as may be found most suitable. The damping members 25 are preferably made of a material having relatively great molecular inertia, such as printer's roll, Glyptal, Du Pont Viscoloid, or the like.

Fig. 4 shows three sets of curves X, Y and Z representing the resonance of the system described above under various conditions. The curve X shows that the low frequency vibration of a system wherein the pickup is rigidly mounted on the pickup arm is quite high. The vibration of a system wherein the pickup head 15 is mounted on the pickup arm 1 by means of the springs 21 alone is shown by the curve Y. Here, it will be seen that there is a fairly sharp peak in the region of about 60 cycles. By adding the damping strips 25 on the springs 21, the resonance of the system is changed to that shown by the curve Z, from which it will be noted that there is a smaller peak at about 80 cycles and that at the extreme, low frequency end, the response drops way down. Thus, with a mounting of the type above described, it is possible to provide a system which will have a resonant peak in the region of around 80 cycles per second and below which the response falls off rapidly. Since the tone arm swinging resonance is usually in the region of about 15 to 20 cycles, it is apparent that, with an improved mounting according to my present invention, the low frequency vibrations of the pickup arm will not be transmitted to the pickup and the distortion normally introduced thereby will be eliminated.

Although I have shown and described but one embodiment of my present invention, it will undoubtedly be apparent to those skilled in the art that many other modifications thereof, as well as changes in the particular one described above, are possible. I therefore desire that my invention shall not be limited except insofar as is made necessary by the prior art and by the spirit of the appended claims.

I claim as my invention:

1. In signal translating apparatus, the combination of a supporting arm, a signal translating device including a needle adapted to cooperate with a phonograph record, means coupling said device to said arm, said coupling means comprising a resilient element secured to each of said arm and device, and a damping element carried by said resilient element.
2. In signal translating apparatus, the combination of a supporting arm, a signal translating device including a needle adapted to cooperate with a phonograph record, means coupling said device to said arm, said coupling means comprising a resilient element secured to each of said arm and said device, and a damping element carried by said resilient element, said damping element having the characteristic of possessing relatively great molecular inertia.
3. In signal translating apparatus, the combination of a supporting arm, a signal translating device including a needle adapted to cooperate with a phonograph record, means coupling said device to said arm, said coupling means comprising a pair of flat springs secured to said device in parallel relation and straddling said arm, said springs being also secured to said arm, and a pair of damping strips secured one to each of said springs, said damping strips being formed of a material possessing relatively great molecular inertia.
4. In signal translating apparatus, the combination of a supporting arm, a signal translating device including a needle adapted to cooperate with a phonograph record, means coupling said device to said arm, said means comprising a pair of flat spring elements secured to said device and extending therefrom in spaced relation, said springs straddling said supporting arm in spaced relation thereto, means connecting said springs to said supporting arm, and damping means secured to each of said springs.
5. In signal translating apparatus, the combination of a supporting member, means mounting said supporting member for movement in a plane across a phonograph record, a signal translating device adapted to cooperate with the record, and a pair of yieldable elements each secured at one end to said device and at its opposite end to said supporting member, said yieldable elements maintaining said device in spaced relation to said supporting member and being yieldable in a direction transverse to said supporting member and parallel to said plane whereby said device is yieldingly carried on said supporting member for movement relative thereto as a whole transversely of said supporting member.
6. Signal translating apparatus according to claim 5 characterized in that said yieldable elements comprise spring members.
7. Signal translating apparatus according to claim 5 characterized in that said yieldable elements comprise leaf springs arranged in planes normal to said transverse direction.
8. Signal translating apparatus according to claim 5 characterized in that said yieldable elements comprise leaf springs one on each side of said device and said supporting member, and characterized further in that said springs are arranged in planes normal to said transverse direction.
9. Signal translating apparatus according to claim 5 characterized by the addition of damping means in association with said yieldable means for damping oscillations thereof.

10. In signal translating apparatus, the combination of a supporting arm, means mounting said supporting arm for movement in a plane across a phonograph record, a pickup device adapted to cooperate with the record, a pair of leaf springs disposed one on each side of said arm and said pickup device yieldably connecting said device to said arm in spaced relation to each other, said springs being disposed to permit relative motion between said device and said arm in a direction transverse to said arm and parallel to said plane, and vibration damping means secured to each of said springs, said damping means being formed of a material having relatively great molecular inertia.

11. Signal translating apparatus according to claim 10 wherein said damping means is carried solely by said springs.

12. In signal translating apparatus for phonographs, the combination of a supporting arm, means mounting said supporting arm for movement in a plane across a phonograph record, a signal translating device including a needle adapted to cooperate with the record, and a pair of yieldable elements each secured at one end to said device and at its opposite end to said supporting

5 arm, said yieldable elements maintaining said device in longitudinally spaced relation to said supporting arm and being yieldable in a direction transverse to said supporting arm and parallel to said plane whereby said device is yieldingly carried on said supporting arm for movement relative thereto as a whole transversely of said supporting arm.
